(57) **CLAIM**

I claim the ornamental design for a four petal dessert, as shown and described.

DESCRIPTION

FIG. 1 is a perspective view of a four petal dessert;
FIG. 2 is another perspective view thereof;
FIG. 3 is a right side view thereof;
FIG. 4 is a top view thereof; and,
FIG. 5 is a bottom perspective view of the empty cup thereof.

1 Claim, 5 Drawing Sheets

FIG. 1

FIG. 2

FIG. 3

FIG. 4
